UNITED STATES PATENT OFFICE

2,501,155

THERMOSTATIC CIRCUIT BREAKER

John D. Bolesky, Attleboro, Mass., assignor to
 Metals & Controls Corporation, Attleboro,
 Mass., a corporation of Massachusetts

Application May 4, 1944, Serial No. 534,092

13 Claims. (Cl. 175—294)

1

This invention relates to circuit breakers and more particularly to thermostatically controlled circuit breakers.

Among the objects of this invention are the provision of improved thermostatically controlled circuit breakers; the provision of circuit breakers which are controlled by a thermostatic member, but do not rely upon the movement of contacts attached to said thermostatic member to interrupt a circuit, the provision of circuit breakers controlled by thermostats but in which the thermostat need not carry the entire current in the circuit; and the provision of circuit breakers of the type indicated which operate efficiently and which last for long periods of time. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

Referring to the drawings in which are illustrated several of the possible embodiments of the present invention.

Fig. 1 is a side elevation of one form of the invention, a cover part being in section;

Fig. 2 is a vertical section of the Fig. 1 device, parts being shown in elevation;

Fig. 3 is a right-end elevation, cover parts being broken away;

Fig. 4 is a horizontal section taken along the line 4—4 on Fig. 2;

Fig. 5 is a horizontal section taken along the line 5—5 on Fig. 2;

Fig. 6 is a view similar to Fig. 2 but showing parts in different positions;

Fig. 7 is a vertical section taken along the line 7—7 in Fig. 1;

Fig. 8 is a top plan of another embodiment of the invention;

Fig. 9 is a side elevation of the Fig. 8 embodiment;

Fig. 10 is an end elevation of the Fig. 8 embodiment;

Fig. 11 is a vertical section taken along the line 11—11 on Fig. 8;

Fig. 12 is a vertical section taken along the line 12—12 on Fig. 8;

2

Fig. 13 is a view similar to Fig. 12 but with parts in different positions;

Fig. 14 is a section taken along the line 14—14 on Fig. 9;

5 Fig. 15 is a top plan view of another embodiment of the invention;

Fig. 16 is a front elevation of the Fig. 15 embodiment;

Fig. 17 is a rear elevation of the Fig. 15 embodiment;

Fig. 18 is a right-end elevation of the Fig. 15 embodiment;

Fig. 19 is a left-end elevation of the Fig. 15 embodiment;

15 Fig. 20 is a vertical section taken along line 20—20 on Fig. 15;

Fig. 21 is a view similar to Fig. 20 but with parts in different positions;

Fig. 22 is a fragmentary view similar to Figs. 20 and 21 but with parts in other positions;

Fig. 23 is a horizontal detail section taken along the line 23—23 on Fig. 20; and

Fig. 24 is a perspective view of a cam operating member of the Fig. 15 embodiment.

25 Similar reference characters indicate corresponding parts throughout the several views of the drawings.

Referring now to the Figs. 1-7 embodiment, numeral 1 is a rectangular case surrounding the principal parts of the structure, being covered by a top 3. The main circuit connections are made to terminals 5 and 7. A bus bar 9 connects terminal 7 with a contact 11. Contacts 11 and 15 may be bridged by bar 17 having contacts

30 19 and 21 on its opposite ends. Terminal 5 and a bus bar 13 are not directly connected to one another. Terminal 5 is on a post 23 which extends through but is electrically insulated from a cylinder 25. Extension plate 27 is attached to

35 cylinder 25 and carries a contact or line terminal 29. The end of post 23 acts as another contact or line terminal 31 insulated from 27. A dished snap-acting thermostat disc 33, of the type disclosed in Spencer Patent 1,448,240, is located

40 above plate 27, and carries adjacent its periphery contacts 35 and 37 which freely engage contacts 29 and 31 so that the disc bridges the latter. The path of the current in the main circuit when closed is accordingly from terminal 7

45 to bus bar 9, contact 11, contact 21, bar 17, con-

46 tact 35, disc 33, contact 37, post 23, cylinder 25, extension plate 27, contact 29, and terminal 31;

47 48 49 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 tact 19, contact 15, bar 13, cylinder 28, plate 27, contact 29, contact 35, disc 33, contact 37, contact 31, post 23 to terminal 5.

Bar 17 is mounted on an insulating cross-bar 39 having a narrow central portion 41 and a wider lower portion 43. Member 39 is mounted upon a post 45. Post 45 carries sliding cylinder 47 which is spaced from member 39 by a collar 49. The bottom of post 45 is enlarged, as shown at 51, to the approximate size of the upper part of the opening 53 in cylinder 47. Between end 51 of post 45 and the top 55 of cylinder 47 is located a coil spring 57.

The opening 53 in cylinder 47 is enlarged at the lower section to receive another coil spring 59 which is seated in another cylinder 61. The spring 59 supports cylinder 47. Post 45 slides in cylinder 47 and collar 49, and cylinder 47 slides in an outer cylinder 63. Cylinder 47 is made of brass or some similar non-magnetic metal while post 45 is of iron or some other magnetic metal.

Surrounding cylinder 63 is a solenoid coil 67 to which current is conducted by leads 69 and 71. An outer case 73 covers the assembly. It is attached to bottom 65 of case 1 by bolts 75. Cylinder 61 is attached to bottom plate 77 of outer case 73 through a headed portion 79. Bus bars 9 and 13 are attached to a supporting insulating base 81 by screws 83.

Disc 33 is loosely mounted at the central portion thereof on a post or stem 85 which has a groove 87 for this purpose. Post 85 has a hollow central portion to accommodate a plug 89 and is slidably mounted in an upper insulating support shelf 91. Shelf 91 has an opening 93 for this purpose, of which the lower portion 95 is enlarged to make room for a coil spring 97. This coil spring is located between the top of enlarged portion 95 and a shoulder 99 on post 85 and biases the disc bodily toward contacts or line terminals 29 and 31. Guide pins 101 are attached to shelf 91 and project through suitable openings in disc 33, to prevent rotation thereof without interfering with its action.

Mounted above shelf 91 is a strip 103 constituting the movable contact member of a holding switch for the solenoid. This has ears 105 for mounting on brackets 107 which are attached to shelf 91. One end of strip 103 carries terminal 109 below which is a coil spring 111. Spring 111 is supported by a cylinder 113 having a headed over-portion 115 and which projects through an opening in shelf 91. The other end of strip 103 carries contacts 117 and 119 on opposite sides thereof. Bracket 121 is likewise attached to shelf 91 and is bent to form a U over strip 103. A contact 123 is attached to this bracket in position to cooperate with contact 117. A contact 125 is mounted on shelf 91 in position to cooperate with contact 119. A terminal 127 is attached to contact 125. A terminal 129 is attached to terminal 109 by a pigtail conductor 131.

A terminal 133 is connected to contact 123 through bracket 121 and a conductor 135. Lead 71 to solenoid 67 is connected electrically to terminal 133 through post 137. Lead 69 is attached to a terminal 139.

The bar 17 is made of a number of laminations of beryllium copper soldered on each end for electrical conductivity. The laminations are not soldered over the entire area of the adjacent surfaces. 15 laminations of about .009 of an inch thick are employed (see Fig. 7). The bar 17 can be made of a solid piece of metal if preferred

and if the advantages of lamination are not desired.

Cross-bar 41 is held in position by two guide posts 141 attached to shelf 91 and plate 27. Posts 141 are made larger at portions 143 than at portions 145. Cross-bar 41 rides on posts 141 only up to portions 143 which act as stops.

The operation of the device is as follows: Figs. 1 and 2 show the position of the device when there is no current passing through the circuit and when thermostatic disc 33 is cold. Assume now that current is passed through the circuit between terminals 5 and 7 and simultaneously through the holding circuit between terminals 129 and 139 (see 129, 131, 109, 103, 117, 123, 121, 135, 133, 137, 71, solenoid 67, 69, 139). The current through the holding circuit energizes solenoid 67 thereby closing the main circuit by pulling down bar 17 until contacts 21 and 11, and 19 and 15 respectively contact each other. It has been found that by the use of laminations in the manufacture of bar 17, the tendency for the bar and its contacts to bounce when the plunger seats and spring 59 is compressed, is substantially decreased.

The path of the main current it will be noted passes through disc 3. The disc, when cold, has the normal form illustrated in Fig. 2 with its center bowed upward. When heated by flow of overload current therethrough, it snaps to the oppositely bowed form of Fig. 6. This lowers plug 89 which had previously maintained contacts 117 and 123 together, permitting strip 103, under the bias of spring 111, to bring contacts 119 and 125 together. This breaks the circuit through holding coil 67, and spring 59 thereupon separates contacts 19 and 21 from contacts 15 and 11 respectively.

The current through the main and the holding circuits may be the same or different value. Thus terminals 5, 7, 129 and 139 may all be connected to the same source of power, or terminals 5 and 7 may be connected to one source of power and terminals 129 and 139 to another source of power. Although the present circuit breaker will interrupt a heavy current passing between terminals 5 and 7, the holding circuit need carry only a small current.

It will be noted that while the disc 33 snaps from its normal bowed form of Fig. 2 to its oppositely bowed form of Fig. 6 when heated by overload current, it remains in bridging engagement with the terminals 29 and 31 after snapping. This is because the disc is biased bodily toward the terminals by the spring 97, which acts to restrain the periphery of the disc against movement away from 29 and 31. While the disc contacts 35 and 37 may disengage momentarily from contacts 29 and 31 as the disc snaps, spring 97 quickly drives the disc downward to re-engage the contacts.

Referring now to Figs. 8-14 a different embodiment of the invention is shown. A case 147 is made up of two sections, a top segment 149 and a bottom segment 151. Mounted in the bottom segment 151 by means of an adjustable center pin 153 is a dished, snap-acting thermostatic disc 155 similar in function to disc 33 of the previous embodiment. This disc carries adjacent its periphery contacts 157 which freely engage contacts or line terminals 159 located in case segment 151. Disc 155 is elongated at the area of contacts 157. Case segment 151 contains an area 161 of the same shape and only slightly larger than the disc 155. The elongated portions

163 of the area 161 enclose the elongated portions of the disc 155 to prevent it from rotating.

In case segment 149 are located U-shaped hollow cylinders 165 in which are coil springs 161. These act against the disc at points adjacent its periphery to bias the disc bodily toward the terminals 159. Also located in segment 149 is a resilient movable contact member 169 having contacts 171 and 173 on opposite sides thereof. Cooperating contacts 175 and 177 are located opposite and cooperate with contacts 171 and 173 respectively. Contact member 169 is attached electrically to terminal 179 and is biased away from contact 175 toward contact 177. Contacts 175 and 177 are electrically attached respectively to terminals 181 and 183.

Disc 155 is loosely mounted on center pin 153 through post 185. Post 185 is slidably mounted in center pin 153 and holds the disc between shoulder 187 and headed over-portion 189.

The two parts 149 and 151 of case 147 are held together by bolts 191. A pin 193 is attached to member 169 to provide a mechanical link between disc 155 and member 169.

The stationary contacts or line terminals 159 are connected by posts 195 to terminals 197. The circuit from one terminal 197 to the other terminal 197 is accordingly from one terminal 197, one post 195, one contact 159, one contact 157, disc 155, other contact 157, other contact 159, other post 195 to the other terminal 197.

The circuit which includes terminals 179, 181 and 183 is controlled by the position of member 169 which in turn is controlled by the position of thermostat 155. Assuming now that thermostat 155 is in the Fig. 11 position, member 169 is forced upward so that contacts 171 and 175 are together (see also Fig. 13). When thermostat 155 has snapped to its position of opposite curvature the pressure on member 169 is relieved and this member assumes the Fig. 12 position wherein contacts 173 and 177 are together.

When the contacts 171 and 175 are together the circuit closed is as follows: Terminal 181 to contact 175, contact 171, member 169, terminal 179. When the device is in the Fig. 12 position the circuit closed is from terminal 183 to contact 177, contact 173, member 169 to terminal 179.

The operation of the device is as follows: The circuit from one terminal 197 to the other terminal 197 passes through disc 155. If this current reaches a dangerously high level disc 155 is heated so that it snaps from the Fig. 13 position to the Fig. 12 position. This snap action breaks the circuit from terminal 181 to terminal 179 and makes the circuit from terminal 183 to terminal 179. The snapping of disc 155 from one position of curvature to another does not operate to break the circuit between terminals 197. The disc center merely moves downward carrying with it post 185 which is slidably mounted, as stated previously, in threaded post 153. Disc contacts 157 remain in engagement with line terminals 159 after the disc has snapped. The shoulder 187 on post 185 operates as a stop but is not located so that the circuit through the disc is broken by the snapping of disc 155. Post 185 has an enlarged portion 199 on the end opposite 189 which operates as a stop when the disc snaps in the opposite direction.

The location of the disc is controlled by the adjustment of threaded post 153. Screwing this post in or out changes the location of shoulders 187 and 199, and thereby affects the snapping temperature of disc 155.

Referring now to Figs. 15-24 another alternative form of the invention is disclosed which is particularly applicable to circuit breakers which are intended for interrupting heavy currents.

5 A main base 201 of insulating material provides a mount. On this base are mounted contact plates 203 and 205. On these plates are respectively contacts 207 and 209. A bus bar or contact member 211 carries contacts 213 and 215 which cooperate with contacts 207 and 209 respectively. Bar 211 is mounted on post 217 and is loosely held thereon between the cylinder 219 and handle 221 by means of spring 223 (see Fig. 21). Handle 221 screws on a threaded extension 225 of post 217. The various parts referred to are kept in alignment by bracket 227 which has a suitable opening to accommodate handle 221.

20 A guide post 229 is attached to base 201 and bracket 227 and cooperates with a finger member 231 attached to bar 211. This finger member and post 229 maintain the bar 211 and its contacts 213 and 215 in position to meet contacts 207 and 209 when the device is in the position

25 shown in solid lines in Fig. 16. The post 217 is bolted to a cam member 233. Member 233 has cam shaped openings 235 on opposite sides thereof of which cooperate with a follower or detent 237. Member 233 slides in a channel 239 which is bolted to base 201 as shown at 241. Follower 237 is held in a slot 243 on each side of the channel 239. Follower 237 can move either up or down said channel in response to the cam action of 235. It will be noted that cam 235 has a notch

30 35 245 providing a latch element at the end nearest post 217. This holds follower 237 when the device is in the position shown in Fig. 17, for example. Springs 247 attached to a bar 249 at one end thereof, which bar 249 is bolted to the member 233, and to the base 201 by a hook member 251, tend to move the cam to the position shown in Fig. 21. Terminals 253 attached to bus bar 255 are connected to bus bar 257 through heater 259. Bus bar 257 is connected to contact

40 45 50 member 205 by a projecting portion which extends through base 201 and to which plate 205 is bolted, as shown at 261.

Terminals 263 are attached to bus bar 265, a projecting portion of which passes through base 201 and to which plate 203 is bolted, as shown at 264.

55 It will be seen that the current passes through terminals 253, bus bar 255, heater 259, bus bar 257, plate 205, contact 209, contact 215, bar 211, contact 213, contact 207, plate 203, bus bar 265 to terminals 263.

60 Follower 237 has attached thereto a central post 267 on which is mounted a thermostatic disc 269. This disc is similar to disc 155 shown in the previous embodiment. To opposite points on the disc are attached contacts 271 and 273 which cooperate with contacts or line terminals 275 and 277 attached respectively to bus bars 257 and 255. The disc 269 therefore shunts the heater 259, but because of the relative current capacities thereof the disc 269 carries only a relatively small proportion of the current.

65 70 75 Insulating shields 279 and 281 are preferably provided to surround the contacts 271, 273, 275 and 277. These shields are held on respectively by bolts 280 and 282. They restrain the periphery of disc 269 against movement away from line terminals 275 and 277.

A manual release button 283 is located close 75 to the handle 221 and is mounted on an exten-

sion 285 of bracket 227. Button 283 is attached to post 287 which passes through an opening in extension 285, the foot of bracket 227, and base 201, to project to the other side of base 201. Channel 239 carries a supporting bracket 289 which is rectangular in shape with an opening 291 therein. This bracket 289 likewise supports a cross pin 293 which has an extending tongue 295, the end of which lies against the end of post 287. Pin 293 extends through both sides of bracket 289 and on each end is mounted a cross-bar 297. These cross-bars carry at their ends, opposite to that at which they are attached to pin 293, pins 299 to which are attached links 301, the other ends of which are attached to follower 237. Pushing button 283 in will, through the linkage described, push follower 237 out of notch 245, whereupon springs 247 can pull the cam assembly to the Fig. 21 position.

The operation of the device is as follows: Contacts 207 and 213, and 209 and 215 are closed by pushing handle 221 down. This closes the circuit through bar 211, tensions springs 247 and seats follower 237 in notch 245. The passage of current through heater 259 heats thermostatic disc 269. When the current passing reaches an undesirable high, disc 269 snaps thereby raising follower 237, which is attached to the center of disc 269, out of notch 245. The springs 247 thereupon return the device to the Fig. 21 position. This opens contacts 207 and 213, and 209 and 215. If the device is in the Fig. 20 position, the circuit can be opened by pressing on knob 283. As explained previously, this raises follower 237 out of notch 245 thereby permitting springs 247 to return the device to the Fig. 21 position.

Since disc 269 is in shunt with heater 259 the disc carries only a small proportion of the current, yet receives the heating effect of the entire current. It will be noted that when the disc snaps from its Fig. 20 to its Fig. 22 position, disc contacts 271 and 273 remain in engagement with line terminals 275 and 277.

Cross-reference under Rule 43 is made to applicant's divisional application, Serial No. 633,239, filed December 6, 1945.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. In a thermostatic circuit breaker, a support, line terminals on the support, a dished, snap-acting thermostatic disc having contacts on one face thereof adjacent its periphery freely engaging said terminals, said disc having a normal form bowed in one direction and adapted to snap to an oppositely bowed form upon heating in response to flow of overload current therethrough, means independent of the line terminals holding said disc in place on the support with its periphery restrained against movement away from the terminals but free of the support and terminals and with its center free to snap so that its contacts remain in engagement with the terminals in either of its oppositely bowed forms, a switch mounted on the support, and means operable by the center of the disc for operating the switch.

2. In a thermostatic circuit breaker, a support, line terminals on the support, a dished, snap-acting thermostatic disc bridging said terminals, said disc having a normal form bowed in one direction and adapted to snap to an oppositely bowed form upon heating in response to flow of overload current therethrough, said disc being mounted on the support for axial movement toward and away from the terminals, means biasing the disc bodily toward the terminals so that the disc bridges the terminals in either of its oppositely bowed positions, the center of the disc being free to snap and its periphery being free of the support and terminals, a switch mounted on the support, and means operable by the center of the disc for operating the switch.

3. In a thermostatic circuit breaker, a support, line terminals on the support, a dished, snap-acting thermostatic disc bridging said terminals having a normal form bowed in one direction and adapted to snap to an oppositely bowed form upon heating in response to flow of overload current therethrough, said disc being mounted on the support for axial movement toward and away from the terminals with its periphery free of the support and terminals, at least one spring biasing the disc bodily against the terminals so as to hold it in engagement with the terminals in either of its oppositely bowed forms while permitting its center to snap, a switch mounted on the support and means operable by the center of the disc for operating the switch.

4. In a thermostatic circuit breaker, a support, line terminals on the support, a dished, snap-acting thermostatic disc having contacts adjacent its periphery freely engaging said terminals, said disc having a normal form bowed in one direction and adapted to snap to an oppositely bowed form upon heating in response to flow of overload current therethrough, the disc being mounted for bodily movement toward and away from the terminals by means of a stem fixed to the center of the disc extending axially therefrom and slideable in the support, a spring biasing the disc toward the terminals to hold the disc contacts in engagement with the terminals when the disc is in either its normal form or oppositely bowed form, the center of the disc being free to snap, and a switch mounted on the support having a movable contact member biased away from a normal non-overload position, said stem engaging said contact member when the disc is in its normal form to hold the contact member against its bias in non-overload position.

5. A circuit breaker comprising a support, line terminals on the support, a dished, snap-acting thermostatic disc freely bridging said terminals, said disc having a normal form bowed in one direction and adapted to snap to an oppositely bowed form upon heating in response to flow of overload current therethrough, said disc being mounted on the support with its periphery free of the support and terminals to remain in position freely bridging the terminals in either of its oppositely bowed forms and with its center free to snap, a solenoid switch mounted on the support and connected in series through the terminals with the disc, and a holding switch for the solenoid mounted on the support and connected in a holding circuit for the solenoid, said holding switch being operable by the center of the disc to open to deenergize the solenoid upon snapping of the disc in response to flow of overload current therethrough.

6. In a thermostatic circuit breaker, a support,

line terminals on the support, a dished, snap-acting thermostatic disc having contacts adjacent its periphery freely engaging said terminals, said disc having a normal form bowed in one direction and adapted to snap to an oppositely bowed form upon heating in response to flow of overload current therethrough, a stem fixed to the center of the disc extending axially therefrom and being slidable in the support to carry the disc for movement toward and away from the terminals, a spring biasing the disc toward the terminals to hold the disc contacts in engagement with the terminals when the disc is in either its normal form or oppositely bowed form, the center of the disc being free to snap, a solenoid switch mounted on the support and connected through the terminals in series with the disc, and a holding switch for the solenoid mounted on the support and connected in a holding circuit for the solenoid, said holding switch having a movable contact member biased away from a normal holding-circuit-closing position, said stem engaging said contact member when the disc is in its normal form to hold the contact member against its bias in holding-circuit-closing position.

7. A circuit breaker comprising a support, line terminals on the support, a dished, snap-acting thermostatic disc having contacts adjacent its periphery freely engaging said terminals, a stem fixed to the center of the disc extending slidably through an aperture in the support and carrying the disc for movement toward and away from the terminals, springs acting against the disc at points adjacent its periphery to bias the disc bodily toward the terminals, a switch mounted on the support having a resilient contact member biased toward the disc and held in a non-overload position against its bias by the center of the disc when the latter is in a first bowed position, said disc being adapted to snap to an oppositely bowed position upon heating in response to flow of overload current therethrough to release said contact member for movement away from its said non-overload position, the springs holding the disc in position for engagement of its contacts with the terminals in either of the bowed positions of the disc.

8. A circuit breaker comprising a support, line terminals on the support, a dished, snap-acting thermostatic disc having contacts on one face thereof adjacent its periphery freely engaging said terminals, said disc having a normal form bowed in one direction and adapted to snap to an oppositely bowed form upon heating in response to flow of overload current therethrough, means on the support independent of the line terminals extending over the periphery of the disc on the side thereof opposite the contacts holding said disc in place on the support with its periphery restrained against movement away from the terminals and with its center free to snap so that its contacts remain in engagement with the terminals in either of its oppositely bowed forms, a switch mounted on the support having a movable contact member biased to open-circuit position, a latch element on said contact member, and a detent operable by the disc and engageable with the latch element to latch the contact member in closed-circuit position against its bias as long as the disc is in its normal form.

9. A circuit breaker as set forth in claim 8, further including a manual control member for releasing the detent manually to open the switch.

10. In a thermostatic circuit breaker, a support, line terminals on the support, a snap-acting thermostatic element having contacts on one face

thereof on opposite sides of its center freely engaging said line terminals, said element having a normal form bowed in one direction and adapted to snap to an oppositely bowed form upon heating in response to flow of overload current therethrough, means independent of the line terminals holding said thermostatic element in place on the support in such manner that the contacts thereon are restrained against movement away from the terminals but free of the support and terminals and with the center of the thermostatic element free to snap so that its contacts remain in engagement with the terminals in either of its oppositely bowed forms, a switch mounted on the support, and means operable by the center of the thermostatic element for operating the switch.

11. In a thermostatic circuit breaker, a support, line terminals on the support, a snap-acting thermostatic element bridging said terminals, said thermostatic element having a normal form bowed in one direction and adapted to snap to an oppositely bowed form upon heating in response to flow of overload current therethrough, 20 said thermostatic element being mounted on the support for movement in opposite directions normal to the general plane of the element toward and away from the terminals, means biasing the thermostatic element bodily toward the terminals 25 so that the thermostatic element bridges the terminals in either of its oppositely bowed positions, the center of the thermostatic element being free to snap and the portions thereof engaging the terminals being free of the support and terminals, 30 a switch mounted on the support, and means operable by the center of the thermostatic element for operating the switch.

12. A circuit breaker comprising a support, line terminals on the support, a snap-acting thermostatic element freely bridging said terminals, said thermostatic element having a normal form bowed in one direction and adapted to snap to an oppositely bowed form upon heating in response to flow of overload current therethrough, 40 said thermostatic element being mounted on the support with the portions thereof which engage the terminals free of the support and terminals to remain in position freely bridging the terminals in either of its oppositely bowed forms and 45 with its center free to snap, a solenoid switch mounted on the support and connected in series through the terminals with the thermostatic element, and a holding switch for the solenoid mounted on the support and connected in a holding 50 circuit for the solenoid, said holding switch being operable by the center of the thermostatic element to open to de-energize the solenoid upon snapping of the thermostatic element in response to flow of overload current therethrough.

13. A circuit breaker comprising a support, line terminals on the support, a snap-acting thermostatic element having contacts on one face thereof on opposite sides of its center freely engaging said terminals, said thermostatic element having 60 a normal form bowed in one direction and adapted to snap to an oppositely bowed form upon heating in response to flow of overload current therethrough, means on the support independent of the line terminals extending over the edge 65 of the thermostatic element on the side thereof opposite the contacts holding the thermostatic element in place on the support with its contact-carrying portions restrained against movement away from the terminals and with its center 70 free to snap so that its contacts remain in en-

gagement with the terminals in either of its oppositely bowed forms, a switch mounted on the support having a movable contact member biased to open-circuit position, a latch element on said contact member, and a detent operable by the thermostatic element and engageable with the latch element to latch the contact member in closed-circuit position against its bias as long as the thermostatic element is in its normal form.

JOHN D. BOLESKY.
